UNITED STATES PATENT OFFICE.

GEORGE W. SHIEBLER, OF BROOKLYN, NEW YORK.

DESIGN FOR A SPOON, &c.

SPECIFICATION forming part of Design No. 20,920, dated July 7, 1891.

Application filed March 26, 1891. Serial No. 386,566. Term of patent 3½ years.

To all whom it may concern:

Be it known that I, GEORGE W. SHIEBLER, a citizen of the United States, residing at Brooklyn, in the county of Kings and State 5 of New York, have invented and produced a new and original Design for the Handles of Spoons and Forks, of which the following is a specification, reference being had to the accompanying drawing, forming part thereof.

10 My design is represented by an elevation.

The leading feature of my design consists in the representation of a female figure with one arm extended to the shank of the fork or spoon-bowl, the end of the handle beneath the 15 figure representing an ornamental pedestal.

a represents the female figure, which in appearance and configuration is loosely robed, and from the head extend projections representing a crown c, and grasped by the left 20 hand is a tablet e, the right arm a' being extended and the right hand grasping the stem

b of the spoon or fork. At the stem b is the representation of a torch b'.

The female figure a is represented as standing upon a pedestal h, and the end of the 25 handle is represented as a shield i, in which is the representation of water, mountains, and the sun. The base of the shield i is ornamented with a serpentine ribbon or scroll i'.

The representation of a bird l, such as the 30 American eagle, with outstretched wings, surrounds the shield adjacent to the pedestal h.

What I claim is—

The design of the ornamental shape and configuration of the fork or spoon handle, 35 substantially as shown and set forth.

Signed by me this 25th day of March, A. D. 1891.

GEO. W. SHIEBLER.
